C. H. KNOX, OF MOUNT PLEASANT, IOWA

Letters Patent No. 66,362, dated July 2, 1867.

IMPROVED CLOTHES-WRINGER.

The Schedule referred to in these Letters Patent and making part of the same.

TO ALL WHOM IT MAY CONCERN:

Be it known that I, C. H. KNOX, of Mount Pleasant, in the county of Henry, and State of Iowa, have made an improvement in Wringers; and I do hereby declare that the following is a full and exact description of the same, reference being had to the accompanying drawings, and letters of reference marked thereon, making a part of this description, in which—

Figure 1 is an elevation of my invention as attached to the end of a washing machine.

Figure 2, an elevation of the end of wringer, showing the lever which holds the rollers together, and a part of the connecting-rod.

Figure 3, a perspective representation of the lower cog-wheel.

Figure 4, a plan view of the suspended roller and the lever to which the weight for regulating the pressure of the rollers is applied.

Figure 5, an elevation of the double cog-wheel which is used in conjunction with wheel shown at fig. 3 in turning the common rubber rollers of a wringer.

The nature of my invention consists, first, in the use of pivoted levers made to bear upon the ends of the upper roller of the common wringer by means of connecting-rods attached to said levers, and a suspended roller at or near the bottom of the washing-box, and a weighted lever attached to the end of the bottom of said box, bearing upon said roller, by which means both ends of the upper roller will be held against the lower roller with equal force, whether the articles to be wrung are put in the wringer at the centre or near either end, which is not the case when metallic or rubber springs are used at each end of the wringer. Second, in the use of an upper double cog-wheel and a central lower pinion, the former having cogs occupying alternate spaces, and the latter being arranged to mesh in said double cog-wheel, and move the rollers of the wringer, notwithstanding said rollers be forced a greater or less distance apart, as when wringing thick or thin articles. This latter arrangement is very important, for the common single cog-wheel is found to be insufficient to turn the rollers of the wringer, especially when they are closed together or far apart, because in the former case the cogs of said wheel are apt to bind, and in the latter case they are apt to be thrown out of gear, or fail to mesh, and only work well when medium-sized goods are put between the rollers.

I claim that the use of my double cog-wheel will obviate the above-named difficulty, as it works equally well whether the rollers of the wringer are far apart or close together; and as the cost of making my style of gearing is but little more than that commonly used, and the difference in friction merely nominal, the advantage gained in this valuable household article is great, not only in its durability but in the convenience of operation. I know that double cog-wheels have been used before, but not for this purpose; I therefore consider the invention a matter of combination.

In order to enable others to make and use my invention, I have marked corresponding parts with similar letters, and will now give a detailed description.

A, fig. 1, represents the end of a common washing machine, to which my wringer is attached. B C show the frame, and D the rollers of a common wringer, the ends B being attached to box A in the usual manner. E, fig. 2, represents a metallic plate, two of which are used, one at each end of the wringer, and rigidly attached to the parts B by a screw, g, or otherwise. These plates E are pivoted at h to levers I, which have circular bearings J, figs. 1 and 2, made to fit the ends of the upper roller D, and hold it in position against lower roller D. Connecting-rods K are secured to levers I, and extend downward to a point a little below the bottom of box A, and are attached to a roller, L, figs. 1 and 4. A lever, M, is hinged to box A at N, and is made to bear upon roller L and force it downward, by which means the levers I are made to press upon the ends of upper roller D, and hold it with suitable force against lower roller D. It will be seen that lever M projects longitudinally under the machine A, and has common notches O in its top, by which means said lever is not in the way, and can have a suitable weight hung in either of said notches to regulate the pressure of said levers I upon roller D, as may be desired, for the purpose of wringing. B B represent the upper double cog-wheel, and S the double pinion used to operate rollers D. It will be seen at figs. 1 and 5 that the cogs of the upper wheel are made to occupy alternate spaces, and that pinion S, fig. 3, is arranged to mesh into said cogs, and thus cause rollers D D to have the same motion. I am not particular as to the material used, but prefer galvanized iron,

it being cheap and not liable to rust. The roller L and the lever M, however, may be made of wood, and answer a good purpose.

Having thus described my invention, what I desire to secure by Letters Patent, is—

1. The arrangement and combination of lever M, hinged to box A, roller L, rods K, levers I, and plate C, arranged to operate upper roller D, as set forth.

2. The double cog-wheel P F, arranged to operate in combination with double pinion S, for turning the rollers D D, substantially as described.

C. H. KNOX.
